UNITED STATES PATENT OFFICE.

FRED C. WALTER, OF CINCINNATI, OHIO, ASSIGNOR TO THE CINCINNATI BALL CRANK COMPANY, OF CINCINNATI, OHIO, A CORPORATION OF OHIO.

DESIGN FOR A BUMPER.

Application filed August 6, 1928. Serial No. 27,720. Term of patent 14 years.

To all whom it may concern:

Be it known that I, FRED C. WALTER, a citizen of the United States, residing at Cincinnati, in the county of Hamilton and State of Ohio, have invented a new, original, and ornamental Design for Bumper, of which the following is a specification, reference being had to the accompanying drawing, forming part thereof.

Figure 1 is a plan view of a bumper impact member.

Figure 2 is a sectional view of the member taken on line 2—2 of Figure 1 illustrating the formation of the ornamental configurations.

Figure 3 is a face view of a bumper.

I claim:

The ornamental design for a bumper as shown.
